STRING GALVANOMETER

Erwin Gerlach, Berlin-Siemensstadt, Germany,
assignor to Klangfilm G. m. b. H., Berlin, Germany, a corporation of Germany

Application August 6, 1935, Serial No. 34,930
In Germany October 5, 1934

3 Claims. (Cl. 171—95)

This invention relates to the recording of sound and has for its principal object the provision of an improved apparatus whereby the zero line of the sound track is shifted for the purpose of obviating or minimizing background noise.

5 It is customary to produce variable area or variable density sound records by means of electrodynamic sound recording apparatus designed to minimize background noise. Such apparatus includes a conductor to which is supplied both an audio current which varies in accordance with the sound to be recorded and a rectified audio current component which varies as the intensity or volume of such sound.

10 This arrangement is disadvantageous because the direct or rectified current tends to raise the thermal load or stress of the electrodynamic system and for the reason that the resistance of the electrodynamic system is extremely low and the 15 current required to cause a shift in the zero line corresponds only to a small fall of potential across the terminals of the electrodynamic system. This is undesirable on the ground that the D. C. must be obtained from the microphone currents 20 by way of amplification and rectification, and that the tubes used in connection therewith present always an internal resistance which is high 25 in contrast with the resistance of the electrodynamic system. The result is that the D. C. energy in major part is consumed in the last 30 tube and becomes utilizable only in minor part in the electrodynamic system. For the A. C. power which is supplied to the electrodynamic system, the conditions are more favorable in that 35 the insertion of a transformer between the last amplifier tube for the voice alternating voltage and the sound recorder device arrangements may be made so that the said last tube furnishes a comparatively high voltage and a correspondingly low current.

40 In accordance with this invention this difficulty is minimized by the provision of an improved recording apparatus so constructed that the median position of vibration of the electrodynamic system energized in accordance with the 45 sound to be recorded is varied by means of an electromagnetic system with response to the volume of the sound.

The invention will be better understood from 50 the following description when considered in connection with the accompanying drawing, and its scope will be pointed out in the appended claims.

55 The single figure of the drawing is a diagrammatic showing of a sound recording oscillograph

constructed in accordance with the invention, certain elements being omitted to simplify the drawing.

In the exemplified embodiment of the invention, 10 denotes the current-traversed wire or ribbon of the electrodynamic system to which is attached a mirror 11. A magnetic field is provided by the magnet 21. The wire 10 is attached to the insulation member 12 and is connected at its opposite ends to the terminals 13 and 14. 10 At the left-hand or looped end of the wire 10 where it presents a bend of 180 degrees there is engaged over a tiny hook 15 the wire 16 of a ferromagnetic system. The left-hand end of the wire 16 is firmly tensioned at point 17. Approx- 15 imately in the middle of the wire 16 is the ferromagnetic body or magnetic core 18. The latter projects into the interior of a coil 20 which is placed in a plane parallel to the plane of the mirror 11. Between the body 18 and the hook 15 20 is a cross piece 19.

In a manner similar to that disclosed by Robinson Patent 1,854,159, the rectified part of the signal is applied to the coil 20 and functions to twist the loop 10 so that the peaks of the low 25 and high amplitude oscillations are maintained more nearly in alignment with one another than would be the case if vibration of the loop were not thus controlled by the coil 20. As applied to the recording of impulses, this has the ad- 30 vantage that the zero reference line of the impulses is shifted from the edge of the record only to the extent required to prevent overshooting the edge of the record.

In the operation of the apparatus the terminals 35 13 and 14 are fed with the audio current corresponding to the sound with the result that the mirror 11 undergoes oscillations at the rate and rhythm of the sound. The center of oscillations of the mirror is displaced by means of the coil 40 which surrounds the ferromagnetic body 18 and is supplied with direct current obtained by recti- 45 fication of part of the audio current. The magnetic core 18 will then occupy and assume posi- 50 tions inside the coil which will change in accordance with the momentary size of this D. C. and thereby will alter the median position of oscillation of the mirror 11. The core 18 is not sub- 55 jected to audio frequency vibrations for the reason that the entire arrangement is immersed in oil. The wire 16 slides over the edge of the cross- piece 19 as the body 18 is displaced.

It will be apparent that this arrangement is useful both for records made by the variable den- 55

sity method and the variable area or multi-peak method.

I claim:

- 5 1. A galvanometer including means movable in accordance with vibrations to be measured, a support for said means, and means operable to shift the position of said support in accordance with a rectified component of said vibrations.
- 10 2. A galvanometer including a looped conductor adapted to receive current corresponding to vibrations to be measured, a reflector mounted on said conductor, conductor supporting means, and electromagnetic means energized in accord-

ance with the amplitude of said vibrations for changing the position of said support.

3. A galvanometer including a looped conductor adapted to receive current corresponding to vibrations to be measured, a reflector mounted on 5 said conductor, a support for said conductor, an armature connected to said support, an electromagnetic means energized in accordance with the amplitude of said vibrations for moving said armature and thereby changing the position of 10 said support in accordance with the amplitude of said vibrations.

ERWIN GERLACH.
